UNITED STATES PATENT OFFICE

ADOLPH T. JOHANSON, OF CHICAGO, ILLINOIS

WINDOW VENTILATOR

Application filed May 26, 1928. Serial No. 280,761.

My invention relates to ventilators in general, but pertains more particularly, but not exclusively, to appliances of that type which are attached to the window-sash, whereby the raising or lowering of the latter will automatically expand or contract the ventilator, so that it may occupy a minimum of space when not in use with the window closed.

10 One of the leading objects of the invention is the provision of an appliance of this character which is simple in structure, which is economical to produce, which is effective in action, and which is unlikely to become damaged or injured in ordinary service.

To this end, the preferred structure comprises a plurality of spaced, horizontal, sloping slats associated with end lazy-tongs mechanisms connected to the companion slideable window-sash, whereby such included, slats or blades are expanded and contracted as the sash is moved up and down to open or close the window.

25 To enable those skilled in this art to fully understand the invention, both from structural and functional standpoints, in the accompanying drawing, forming a part of this specification, I have illustrated in detail a present, preferred embodiment of the invention, and in the views of such drawing, like reference characters have been employed to designate the same parts.

In this drawing:—

Figure 1 is a central, vertical section 35 through the window-sash and the connected ventilator, showing the window open and the ventilator in action; and

40 Figure 2 is a similar view illustrating the window in closed condition and the ventilator collapsed.

Referring to this drawing, it will be noted that the window-casing has been designated 11, the window-sill 12 and the vertically sliding window-sash 13.

45 The ventilator comprises a suitable number of horizontally-arranged, vertically-spaced, transversely-sloping, sheet-metal slats or blades 14, each of which at one end has an integral, downturned, cross-flange 15, longer than the width of the blade and con-

stituting a link, formed as a unit with the blade or shutter.

The center of each such link flange is pivotally connected at 16 to the middle of a link 17 of equal length and hinged at one end at 18 to one end of the flange link 15 of the slat or blade just above and hinged at its opposite end at 19 to the other end of the flange link 15 of the blade or slat immediately below.

Thus the several connected links 15 and 17 form the well-known lazy-tongs construction which is easily capable of elongation and shortening.

The lower ends of each lowermost pair of links 15, 17 are pivotally connected at 23 to a bracket 24 mounted on the window-sill by screws 25, 25 by a pair of short links 21, 22, and, in similar manner, the upper ends of each pair of topmost links 15, 17 are pivotally joined to short links 26, 27 hinged at 28 to a depending ear 29 on a sloping cover-plate 31 having an upstanding marginal flange 32 fastened to the sides of the window-sash by one or more screws 33.

To close the ends of the ventilator, each end of the latter is supplied with an upright, metal plate 34, reaching upwardly from the window-sill the proper distance, and having an outstanding, border flange 35 fastened in any approved fashion to the window-casing and an inturned, marginal flange 36 which covers and conceals the adjacent lazy-tongs structure.

When the window is closed with the window-sash in its down position, as indicated in Figure 2, the ventilator, as a whole, is collapsed or contracted, the slats or blades being relatively close together so that the structure occupies but comparatively little space in such inoperative condition.

When, however, the window-sash is raised to open the window, as shown in Figure 1, the upward travel of the cover-plate 31 expands or elongates the pair of lazy-tongs structures at the two ends of the ventilator and the latter is opened up to afford more space between the slats and to tilt the latter to greater degree, whereby to advantageously

deflect the entering air currents and to preclude the admission of rain or snow.

The end plates prevent the air from entering the room except through the gaps between the slats and the top plate constitutes an appropriate cover to overlie the space between the ventilator and the window-sash and to form a connecting operating means between the two.

10 From the foregoing, it will be clear that the ventilator is actuated mechanically and automatically merely through the usual operations of opening and closing the window.

Those acquainted with this art will readily 15 understand that this invention, as defined by the appended claims, is not limited or restricted to the precise and exact details of structure and that these may be modified within comparatively wide and radical limits 20 without departure from the heart and essence of the invention and without the loss of any of its material and substantial benefits and advantages.

I claim:

25 1. The combination of a window-casing, a window-sill, a window-sash slideable in said casing, a plurality of spaced slats each having at each end an integral flange constituting a link, links connecting the centers of such flange links to the opposite ends of the flange links above and below it, brackets on said window-sill, links connecting the lowermost of said flange links to said brackets, a cover-plate mounted on and movable with 35 said window-sash, links connecting the topmost flange links to said cover-plate, whereby opening and closing of the window-sash automatically expands and contracts the ventilator slats, and end-plates mounted on said 40 window-casing outwardly beyond said links and having inwardly disposed flanges concealing said links.

2. The combination of a window-casing, a window-sill, a window-sash slideable in said 45 casing, a plurality of spaced slats each having at each end an integral flange constituting a link, links connecting the centers of such flange links to the opposite ends of the flange links above and below it, brackets on 50 said window-sill, links connecting the lowermost of said flange links to said brackets, a cover-plate mounted on and movable with said window-sash, and links connecting the topmost flange links to said cover plate 55 whereby opening of the window-sash automatically expands and closing of the window-sash automatically contracts the ventilator slats, the latter in the open condition of the window-sash sloping outwardly downwardly.

60 In witness whereof I have hereunto set my hand and seal.

ADOLPH T. JOHANSON. [L.s.]
